J. Stuart Freeman,
Attorney.

UNITED STATES PATENT OFFICE

2,046,099

LATCH FOR HEDDLE FRAMES

John Walker, Jr., Melrose Park, Pa., assignor to
Walker Manufacturing Company, Inc., Philadelphia, Pa., a corporation of Pennsylvania

Application October 19, 1933, Serial No. 694,268

6 Claims. (Cl. 139—92)

The object of the invention is to provide improvements in latches of that type which are especially designed and particularly adapted for use in the heddle frames of looms for the purpose of 5 operatively positioning the customary heddle bars in a definite predetermined relation with the frame itself and with respect to each other.

In heddle frames which are generally of considerable length, it is necessary to support the usual 10 heddle bars at one or more points intermediate of their ends, in relatively fixed relation with respect to the rails of the said frames, yet the support must be of such character as to permit the heddles carried by said bar to be readily shifted 15 past the positions of such supporting means, whenever and in such number as may be desired.

Another object, briefly stated, is to provide in the 20 present invention a combined simplification of an improvement over certain earlier structures in the particular art involved, making use of details which have proved of distinct value, and adding 25 to them the cooperation of additional details which are novel and particularly characteristic of the present disclosure.

25 A further object is to provide in a device of this character a shank, normally secured to one of the rails of a heddle frame, and preferably also adjustable with respect to such rail, said shank being provided with a flattened and broadened head 30 having a cut-out portion adapted to receive a heddle bar inserted laterally thereinto, in combination with a sleeve having an outwardly directed notch adapted to receive such heddle bar when the latter is in operative position, said sleeve being yieldingly 35 maintained in such outermost position by means of a suitable spring, which in this instance is illustrated as a helical compression spring surrounding the said shank, said heddle bar being released for lateral disengagement from said head 40 by and upon the longitudinal shifting of said sleeve against the tension of said spring, and until said sleeve is out of transverse alignment with such bar, the movement of such sleeve outwardly being preferably limited by a diagonal or other 45 irregular arrangement or shape of the free end portion of said head, and said sleeve being limited in its inward movement by the unflattened portion of said shank, over which either one or both sides of said sleeve are adapted to slide. Herein 50 reference is made to the outward or inward movement of the sleeve, and the corresponding portions of the shank head, as the terms "upper" and "lower" become confusing, when it is realized that for each latch in the position shown in Figs. 55 2-7, a corresponding latch is arranged opposite thereto in upright or inverted position.

In addition to the foregoing, the present invention 60 comprises further details of construction and operation, which are fully brought out in the fol-

lowing description, when read in conjunction with the accompanying drawing, in which

Fig. 1 is an elevational view of a heddle frame in which are employed a pair of supporting latches comprising one movement of the invention; 5

Fig. 2 is an enlarged fragmentary elevational view of a portion of one of the heddle rails partly in section in order to show the adjustable positioning therein of the shank of one of the improved latches. 10

Fig. 3 is a section on the line 3—3 of Fig. 2, showing the sleeve operatively engaging a heddle bar;

Fig. 4 is a similar section, showing the sleeve in withdrawn position, and without a heddle bar positioned in the latch; 15

Fig. 5 is a front elevation of the latch and rail, the sleeve being shown in section along the line 5—5 in Fig. 4;

Fig. 6 is a view similar to Fig. 4 but showing the latch from the opposite side; 20

Fig. 7 is a view similar to Fig. 4, but showing the sleeve in extreme outermost position; and

Fig. 8 is an enlarged end elevation of the end of the improved latch. 25

Referring to the drawing, a heddle frame is here shown as comprising parallel, oppositely positioned top and bottom rails 1 and 2, connected at their ends by any suitable means such as straps 3. Either single, or pairs of heddle-supporting bars 4 and 5 extend longitudinally of the frame 30 parallel with and slightly spaced from the neighboring rails 1 and 2, and operatively support corresponding series of heddles 6, only portions of which series are shown.

Each of the rails 1 and 2 is provided at one or 35 more intermediate points with a normally vertically extending bore 7, into which adjustably extends a bolt comprising a threaded shank 8 and an unthreaded portion 9, which latter extends freely from and beyond that surface of the rail directed 40 towards the other of said rails, the freely extending portion of said shank in turn being flattened to provide a transversely wider head 10, separated from said shank by oppositely positioned shoulders 11, and provided with a laterally inwardly 45 extending preferably rectangular recess or cut-out region 12, beyond which the free angularly directed end portion 13 of said head forms one side of said recess, and at its lateral terminal portion is angularly deflected at 14, for a purpose here- 50 inafter described.

A sleeve 15 preferably entirely surrounds said head at 16 and is flattened in cross section, in order to closely yet slidably fit the adjacent surfaces of said head. The lowermost portion 55 of said sleeve, as shown in the drawing, but in reality the outermost portion of said sleeve, since the latter is used both in depending and upwardly extending positions, is provided in its opposite walls with aligned-U-shaped slots or ap- 60

5 ertures 17, adapted to receive and at least partially encircle the laterally opposite sides and one edge of a heddle bar, as shown in Figs. 2 and 3, when said sleeve is in its outermost or operative position.

10 At the opposite end of said sleeve, its opposed walls are provided either with a cut-out region or recess 18, or with an outwardly expanded portion 19, in order to permit the normally forward and rear portions of said sleeve to pass upwardly above (as in Figs. 2 to 7 inclusive) the level of the shoulders 11, when said sleeve is manually shifted rearwardly, and free from engagement with the heddle bar 4 (or for 15 that matter the heddle bar 5), when said latch is in the lower position as shown in Fig. 1. Slidably surrounding the shank 9 is a washer 20 between which and the adjacent surface of the frame rail is positioned a helical spring 21, which 20 also surrounds said shank, and thru said washer cooperates with the adjacent end of said sleeve, to maintain the latter in its normally outermost or operative position as shown in Figs. 1, 2, 3 and 7.

25 30 35 It will be noted at this point, and particularly by reference to Figs. 7 and 8, that in its outermost position said sleeve is prevented from shifting beyond a predetermined point and becoming separated from said head, by direct engagement with the deflected terminal portion 14, when said heddle bar is in operative position within or supported by said bracket in a manner above described. Also, said sleeve may be made by flattening and properly recessing an initially cylindrical tube, or may be formed by punching or otherwise severing a so-called blank from a larger piece of sheet metal, and thereafter folding said sleeve in such a manner as to provide in effect a flattened sleeve, similar to 40 that hereinbefore described and shown in the drawing, the method of forming such sleeve not, however, being an essential part of the invention.

45 I am aware that the invention may be embodied in other specific forms without departing from the spirit or essential attributes thereof, and I therefore desire the present embodiment to be considered in all respects as illustrative and not descriptive, reference being had to the appended claims rather than to the foregoing description to indicate the scope of the invention.

50 55 Having thus described my invention what I claim as new and desire to secure by Letters Patent of the United States is:—

50 60 65 70 75 1. A latch for heddle frames, comprising a cylindrical shank, a flattened head of less thickness than said shank, providing laterally protruding shoulders, said head having a recess adapted to receive a heddle bar, a sleeve comprising a flattened portion slidable over and conforming in cross-section substantially to said head, and also comprising a tongue operative in one position of said sleeve to prevent a bar from accidental dislodgment from within said recess, said sleeve also comprising a substantially cylindrical portion slidable over said shank and said shoulders, and means to limit the movement of said sleeve upon said head generally away from said shank.

70 75 80 85 90 2. A latch for heddle frames, comprising a cylindrical shank a flattened head of less thickness than said shank, providing laterally protruding shoulders, said head having a recess

adapted to receive a heddle bar, a sleeve comprising a flattened portion slidable over and conforming in cross-section substantially to said head, and also comprising a tongue operative in one position of said sleeve to prevent a bar from accidental dislodgment from within said recess, a spring surrounding said shank to force said sleeve towards the free end of said head, said sleeve also comprising a substantially cylindrical portion slidable over said shank and 10 said shoulders, and operative to prevent said spring from engaging said shoulders, and means to limit the movement of said sleeve upon said head generally away from said shank.

3. A latch for heddle frames, comprising shank 15 and head portions, one of which is substantially cylindrical while the other is flattened and of less thickness than the first, providing laterally protruding shoulders at their point of union, said head having a recess adapted to receive a 20 heddle bar, and a sleeve having relatively cylindrical and flattened portions conforming in general to and slidable over said first-mentioned portions respectively, and an extension on said sleeve which, when in one position, is adapted to 25 cooperate with and prevent the accidental escape of a bar from within said recess.

4. A latch for heddle frames, comprising shank and head portions, one of which is substantially cylindrical while the other is flattened and of 30 less thickness than the first, providing laterally protruding shoulders at their point of union, said head having a recess adapted to receive a heddle bar, and a sleeve having relatively cylindrical and flattened portions conforming in 35 general to and slidable over said first-mentioned portions respectively, an extension on said sleeve which, when in one position, is adapted to cooperate with and prevent the accidental escape of a bar from within said recess, and a spring 40 operative to force said sleeve into cooperation with a bar in said recess.

5. A latch for heddle frames, comprising shank and head portions, one of which is substantially cylindrical while the other is flattened and of 45 less thickness than the first, providing laterally protruding shoulders at their point of union, said head having a recess adapted to receive a heddle bar, and a sleeve having relatively cylindrical and flattened portions conforming in 50 general to and slidable over said first-mentioned portions respectively, an extension on said sleeve which, when in one position, is adapted to cooperate with and prevent the accidental escape of a bar from within said recess, and a spring 55 operative to force said sleeve into cooperation with a bar in said recess, said sleeve also preventing said spring from engaging said shoulders.

6. A latch for heddle frames, comprising a cylindrical shank, a flattened head of less thickness than said shank, providing laterally protruding shoulders, said head having a recess adapted to receive a heddle bar and a sleeve comprising a flattened portion slidable over and conforming in cross-section substantially to said head, and also comprising a tongue operative in one position of said sleeve to prevent a bar from accidental dislodgment from within said recess, said sleeve also comprising a substantially cylindrical portion slidable over said shank and said shoulders.

JOHN WALKER, JR.
